SELF-DUMPING ASH TRAY

Filed June 4, 1951

UNITED STATES PATENT OFFICE

2,652,837

SELF-DUMPING ASH TRAY

George J. Conrad, Baltimore, Md.

Application June 4, 1951, Serial No. 229,709

2 Claims. (Cl. 131—240)

1

This invention relates to ash trays and more particularly to those used for holding lighted cigars, cigarettes and the like and retaining their butts and ashes.

It is an object of this invention to provide an ash tray suitable for holding lit cigarettes and cigars, that will automatically dump the lit article when it burns down to a predetermined length and operates its mechanism, to dump the lit article into the tray, and prevent the lit article from falling out of the tray and burning the surroundings.

Another object of the invention is to provide a new and improved self dumping ash tray that will enable a lighted cigarette or cigar when laid on the tray to keep burning until it burns beyond a certain limit where its heat automatically dumps the lighted article into the tray.

An additional object of this invention is to provide a new and improved ash tray that will have the features indicated, and at the same time be attractive in appearance, effective in operation and economical to manufacture.

For a better understanding of the invention and the objects thereof reference is made to the accompanying drawings employed to illustrate a particular form and which are described in the following specification. The claims emphasize the scope of the invention.

In the drawings:

Figure 1 is a perspective view of an ash tray embodying this invention;

Figure 2 is a plan view of the ash tray;

Figure 3 is a sectional elevation taken on line 3—3 of Figure 2;

Figure 4 is a sectional elevation taken across the ash tray on line 4—4 of Figure 2; and

Figure 5 is a detail indicating the structure of the mechanism for dumping a cigarette held by its rest.

Similar reference characters refer to the same parts throughout the drawings.

In the structure shown in Figure 1, a tray 10 is of open rectangular walled construction, made interiorly deep enough to hold a large quantity of cigarette butts and ashes. It is mounted on a base 11 having an open space in its center. A movable ash pan slide 12 forms the bottom of the tray 10 and supports the butts and ashes dropped thereon until said pan is pulled out to dump them from the tray through an opening 13 in the base 11. The walls 14 of the tray are arcuately formed at 15 and are flat at 15 to facilitate its use. The handle 16 of the pan 12 is bent to enable the user to manipulate it conveniently.

2

The pan 12 runs in channels or guides 17 engaging its lateral rims to enable it to be so moved.

Supported on two of the walls of the tray are holding frames 20 each consisting of a pair of side members 21 with holes therein for the support of an axle 22 which is rigidly attached to a cigarette holder 23 that can rotate therewith about its longitudinal axis. The holder 23 is made of metal or some other fireproof and heat conducting material. To keep the holder 23 steady, a thermostatic bimetallic or expansible heat actuated strip 24 is formed into a coiled spring 18 with one end portion 25 rigidly attached to the adjacent wall of the tray. The other end portion 26 of spring 18 is secured to the holder 23, at a point thereof offset from the longitudinal axis of the holder so that when the strip expands or contracts it will actuate the holder and rotate it about the longitudinal axis 20 of axle 22 outwardly from the wall and dump the lit cigarette butt into the ash tray. When the heat is dissipated the holder returns to its normal position. When the lit cigarette butt 30 is placed on the holder it will, when burned down enough, bring its lit portion directly against the holder 23 and heat it. This heat is conducted through the strip 24 and expands it, tilts the holder and dumps the lit cigarette into the tray. With the heated portion of the cigarette discarded and away from the strip, the latter cools off and shrinks to its former length, pulling the holder back rotatively to its former position, ready to receive another cigarette lit or otherwise. When there are a great many butts and ashes in the tray, the user takes the latter to a dustpan, pulls out the pan 12 and dumps them. A slanting metal plate 27 attached to the wall under the holder acts as a stop for the holder 23 in its dumping stroke. The holder surface is arranged so that the cigarette can rest on it without falling off.

While but one general form of the invention is shown in the drawing and described in the specification, it is not desired to limit this application for patent to this particular form, as it is appreciated that other forms could be made that would use the same principles and come within the scope of the appended claims.

Having thus described the invention, what is claimed is:

1. As an article of manufacture, an ash tray, a pair of spaced-apart side members carried by the ash tray, an axle having its ends housed in said members, said ends being rotatable in said members, a cigarette holder mounted on said axle

and fast therewith, and a thermostatic element coiled about said axle, said element having one end secured to the ash tray and its opposite end secured to the holder at a point thereof offset from its longitudinal axis, whereby expansion of the element due to heat imparted thereto by a burning cigarette on the holder rotates the axle and tilts the holder to force the cigarette into the ash tray and thereafter, contraction of the element will restore the holder and axle to their 10 normal position.

2. An article of manufacture as set forth in claim 1 wherein the ash tray is provided with a stop member arresting the tilting movement of the holder, said stop member extending from the 15

inner side of the ash tray between the upper and lower end portions thereof and having a portion directly below the cigarette holder to contact said holder.

GEORGE J. CONRAD.
